UNITED STATES PATENT OFFICE.

JOHN A. CARTWRIGHT, OF CALDWELL, IDAHO.

ROTARY HARROW.

Application filed May 15, 1920. Serial No. 381,760.

To all whom it may concern:

Be it known that I, JOHN A. CARTWRIGHT, a citizen of the United States, residing at Caldwell, in the county of Canyon and State of Idaho, have invented a certain new and useful Improvement in Rotary Harrows, of which the following is a specification:

My invention relates to improvements in harrows, and more particularly to rotary harrows; in which two revolving harrows, with teeth of uniform length, operate by revolving inward, on spindles placed in the center of each harrow, drawn and controlled by two wooden arms, one attached to the spindle of each harrow, and connected with the draw-bar or double-trees by means of iron straps perforated to receive a journal pin, making the connection with the double-trees about two inches on each side of the center of such double-tree or draw-bar; and the objects of my improvement are, first, an upright or vertical spindle for the harrows; second, to provide inward revolutions of the harrows, with the teeth running at uniform depths; third to reduce the friction of the spindle and the arms connecting the harrows with the draw-bar or double-trees; fourth, the causing of the harrows to revolve inwardly, by reason of the pressure applied to the rear of the spindles in drawing the harrows forward, the arms being connected with the draw-bar or double-trees at angles of about forty-five degrees from the center of each harrow; fifth, to construct a rotary harrow which will be self cleaning, and which will efficiently cultivate and pulverize the soil at a uniform depth, and which can be readily swung to turn corners; sixth, to provide a rotary harrow having great strength and rigidity compared with the weight of its parts, which is simple in construction, and economical to manufacture; seventh, to provide inward revolutions of the harrows, without the necessity for elevating the sides of the harrows, either inwardly or outwardly, to cause the harrows to revolve; further objects will appear from the detailed description illustrated in the accompanying drawing, in which—

Figure 1 is a plan of a harrow embodying this invention; Fig. 2 is a rear elevation; Fig. 3 is an enlarged detail in section on the line 3—3, Fig. 1; Fig. 4 is a plan of the journal bracket shown in Fig. 3; Fig. 5 is a plan of the connections of the arms to the draw-bar or double-trees.

Similar numerals refer to similar parts throughout the several views.

The harrow comprises two rotatable frames, each consisting of channel bars 12 crossing one another. These channel bars are perforated to receive the harrow teeth 13 each of which is provided with a reduced threaded portion extending through the channel and forming a shoulder engaging the channel web. The reduced threaded portion is adapted to engage a nut mounted between the channel flanges, and retained in position thereby. The tooth is inserted by screwing it into the nut. Separate bolts are provided for securing the channels together. The teeth are inserted in the bars at the points indicated on Fig. 1.

At the center of each frame, and at the crossing of two of the bars 12, is mounted a journal bracket 2, having radial arms. The arms of the bracket are perforated and bolted to the channel bars between the flanges as at 6. Rising vertically from the bracket, and at right angles thereto is a spindle 1, and therefore at right angles to the harrow.

Arranged to engage the spindle 1 is a journal mounted on a bracket 4 adapted to engage and be secured to a coupling pole 3 by means of bolts. Bracing the coupling pole to the spindle is an iron brace 5 secured to the coupling pole by means of bolts. Arranged to engage the spindle below the bracket 4 is another journal mounted on a bracket 14 adapted to engage and be secured to the brace 5 by means of bolts. Immediately above the base of the spindle, and arranged to engage the spindle is a journal mounted on a bracket 7, which is secured to the arms 8 by means of bolts, being so adapted to engage the end of such arm. The base of the spindle 1 is secured solidly to the journal bracket 2. Connecting the two frames and adapted to engage the journal brackets 4 at each end is a wooden coupling pole 3. Connecting the spindles 1 with the double trees 11 are wooden arms 8 running at angles of forty-five degrees from the respective spindles and arranged to attach to the double-trees by means of cotter pins 10. Adapted to engage the arms 8 and attached to the double trees is a brace 9 which is perforated at the end to receive the cotter pin 10 and passes beneath the double trees 11. This brace 9 is bolted to the arms 8.

Upon reference to Fig. 2 it will be noted

that the bearings formed in the journals 4, 7 and 14 are so arranged that the spindle 1 is at right angles to the harrow frame. This serves to keep the harrow level thereby causing all of the teeth to penetrate the soil at a uniform depth. The angles of the arms 8 cause the harrows to rotate inwardly when drawn forward. Since the arms 8 are pivoted to the spindles 1 and are also pivoted 10 to the cotter pins 10 in the double-trees 11, corners can be readily turned because of the link construction permitting the arms to swing with the turn. This construction is also responsible for the inward rotation of 15 the harrows.

The invention therefore accomplishes its objects. A harrow is produced which will rotate inwardly without unnecessary friction. The parts are so constructed that a 20 rigid structure is produced. This is more particularly accomplished by the rigid construction of the coupling pole and the bracing at the ends of the coupling pole; the construction of the arms and the bracing at 25 the ends attached to the double-trees. The harrow teeth can be readily unmounted, cleaned and replaced.

It is obvious that various changes may be made in the details of the construction 30 without departing from the spirit of this

invention. It is, therefore, understood that this invention is not to be limited to the specific construction shown and described.

I am aware that prior to my invention rotary harrows have been made, but having 35 thus described my invention I claim:

In an apparatus of the class described, coacting rotative harrow devices, a stud rising from the center of each harrow device, a bridging member, means for coupling the bridging member to swing without vertical play or lateral play upon the upper end of each of said studs and operating to couple the harrow devices, an evener beam adapted to receive draft appliances, braces connected 40 at one end to said bridging member and respectively engaging the studs in spaced relation to the bridging member, and swinging without vertical or lateral play thereon, and a pull bar rotatively engaging each of said 45 studs adjacent each harrow device without vertical or lateral play thereon and pivoted at the opposite ends to the evener beam.

In testimony whereof, I affix my signature in the presence of these two witnesses.

J. A. CARTWRIGHT.
